UNITED STATES PATENT OFFICE.

DAVID HOMER HAYDEN, OF NEW YORK, N. Y.

SUPPORTING-CAGING FOR THE COMPOSITION COVERING OF STRUCTURAL MEMBERS.

1,201,463.

Specification of Letters Patent. Patented Oct. 17, 1916.

Application filed October 26, 1912. Serial No. 728,001.

To all whom it may concern:

Be it known that I, DAVID HOMER HAYDEN, a citizen of the United States, and a resident of the city, county, and State of 5 New York, have invented certain new and useful Improvements in Supporting-Cagings for the Composition Covering of Structural Members, of which the following is a full, clear, and exact description.

10 The improvement relates to supporting caging or reinforcement for the concrete and like composition covering of structural members and seeks to provide a simple, inexpensive supporting caging or reinforcement 15 which can be readily applied to structural members of different shapes and securely held in position with portions thereof in predetermined offset relation to the members.

20 The invention consists in the features of improvement hereinafter set forth, illustrated in different forms in the accompanying drawings and more particularly pointed out in the appended claims.

25 In the drawings, Figure 1 is a perspective view of the lower portion of an I-beam with one form of the improved reinforcement applied thereto. Fig. 2 is a cross section of the parts shown in Fig. 1. Fig. 3 is an inverted plan view thereof. In Figs. 2 and 3 part of 30 the reinforcement is expanded and a portion is unexpanded to illustrate the manner of applying the supporting caging or reinforcement to the beam. Figs. 4, 5 and 6 are views similar, respectively, to Figs. 1, 2 and 3, 35 illustrating a modified form of the invention. Fig. 5^a is a view similar to Fig. 5, illustrating a slight modification. Figs. 7, 8 and 9 are views similar, respectively, to Figs. 1, 2 and 3, illustrating a further modification. 40 Fig. 10 is a cross section of an angle bar showing a form of the invention adapted to be applied thereto. Fig. 11 is an elevation of parts shown in Fig. 10 and Fig. 12 is an inverted plan view thereof. Fig. 13 is a 45 cross section of a Z-bar with a form of the invention applicable thereto. Fig. 14 is an inverted plan view of the parts shown in Fig. 13 with a portion of the reinforcement expanded and a portion unexpanded.

50 The improved reinforcement comprises a series of connected cross stays which are formed of a continuous length of wire bent back and forth upon itself. Portions of the wire from which the cross stays are formed 55 are arranged at right angles to the plane or planes of the series of cross stays and are

bent to form attaching elements or hooks. The cross stays themselves are arranged in different planes and preferably each alternate cross stay is arranged in one plane and 60 the other cross stays in a different plane. The two planes extend longitudinally of the member to which the reinforcement or supporting caging is to be applied.

65 The improved reinforcement or supporting caging is adapted to be shipped in compact and unexpanded condition, but in applying the same to the structural member or shape, it is expanded so that the cross stays extend back and forth over the face of the 70 member. Upon the expansion of the strip, the attaching elements hook over the edges of the structural member and portions of the cross stays engage the outer faces thereof to thereby limit the expansion and hold the 75 other portions of the caging in predetermined offset relation with respect to the structural member.

80 In all forms illustrated, the supporting caging or reinforcement is formed of a continuous length of wire bent back and forth upon itself to form the cross stays. In the form shown in Figs. 1, 2 and 3, which is particularly applicable to the reinforcement of the concrete covering upon the lower face of 85 the horizontal I-beam or similar shape, the alternate cross stays 10 are arranged in one plane and the other cross stays 11 are arranged in a different parallel plane offset laterally from the plane of the cross stays 90 10. The intermediate portions between the cross stays 10 and 11 are arranged in planes substantially at right angles to the planes of the cross stays 10 and 11 and are bent to 95 form attaching elements or hooks 12 and connecting and reinforcing elements 13. The attaching hooks extend upwardly and inwardly from the ends of the upper or inner cross stays 10, so that, when the reinforcement or supporting caging is expanded, 100 the cross stays 10 will abut snugly against the face of the I-beam 14 and the attaching elements will hook over and engage the edges and the inner faces of the flanges of the I-beam, as clearly shown in Fig. 2. The 105 connecting and reinforcing elements 13 extend between the ends of the hooks 12 and the ends of the cross stays 11 and are so arranged that when the supporting caging is applied to the beam, these portions and the 110 cross stays 11 are held in predetermined offset relation with respect to the beam, so as

to properly support or reinforce the concrete covering therefor. In this form, the connecting elements 13 are curved and are adapted to extend about the edges of the flanges of the I-beam 14 and in offset relation thereto to properly reinforce the body of concrete extending about the flanges. In Fig. 1, the body of concrete 15 in which the I-beam 14 and the reinforcement or supporting caging are embedded, is indicated in dotted lines.

In its collapsed or unexpanded condition, the distance between the inner ends of the attaching elements or hooks is such that the reinforcement can be placed over the base flange of the I-beam, as indicated in Figs. 2 and 3. Upon the expansion of the reinforcement, the adjacent cross stays 10 and 11 are drawn apart so that they extend back and forth in zig-zag fashion over the face of the I-beam, and the attaching elements 12 are drawn together to snugly engage and hook over the edges of the flanges of the beam. The complete engagement of the attaching elements with the flanges of the beam serves to limit the expansion and hold the reinforcement in position on the beam with the cross stays 10 against the lower face thereof and the alternate cross stays 11 and reinforcing elements 13 in predetermined offset relation to properly reinforce the concrete or composition covering. The engagement of the alternate cross stays 10 with the face of the beam aids in limiting the expansion of the reinforcement and the construction is such that the attaching elements or hooks cannot be distorted by the force applied in expanding the reinforcement. Inasmuch as the expansion is positively limited, the amount of reinforcement per lineal foot can be accurately predetermined by properly proportioning the dimensions of the parts of the reinforcement in accordance with the size of the beam to which it is to be applied.

In the construction shown in Figs. 4, 5 and 6, the alternate cross stays 20 and 21 are also arranged in two parallel planes, the cross stays 20 being adapted to engage the outer face of the beam 14 and the cross stays 21 are held in offset relation thereto. Upwardly and inwardly extending hooks or attaching elements 22 similar to the hooks 12 previously described, are formed upon the ends of the inner cross stays 20. Portions 23 extend upwardly and outwardly from the ends of the hooks 22 and thence downwardly closely adjacent the vertical portions of the hooks and also abut against the edges of the flanges of the beam when the reinforcement is expanded. Connecting and reinforcing portions 24 extend from the lower ends of the portions 23 outwardly and thence downwardly to the ends of the cross stays 21. These reinforcing and connecting elements

24 serve to properly reinforce the portion of the concrete which extends about the edges of the flanges of the beam. The portions 22 and 23 form, in effect, hooks with double shanks which abut against the edges of the beam when the reinforcement is expanded and aid one another in resisting the strain brought upon the reinforcement in effecting its expansion. In the construction shown in Fig. 5^a the attaching elements or hooks and the ends of the cross stays 20 comprise upturned portions 22^a which are adapted to extend upwardly above the flange of the beam and which are bent inwardly and downwardly and thence outwardly to form horizontal portions 22^b which engage the upper or inner face of the flange. These horizontal portions extend across and engage the vertical portions 22^a and curved connecting and reinforcing portions 24^a extend from the horizontal portions 22^b outwardly and downwardly to the cross stays 21.

In the form shown in Figs. 7, 8 and 9, the alternate cross stays 30 and 31 of the series are arranged in two intersecting planes which, when the reinforcement is applied to the beam 14, are inclined at an acute angle to the outer face of the beam. One end of each of the cross stays 30 and 31 is provided with a hook 32 and a connecting and reinforcing element 33 extends from the end of the hook to the end of the next adjacent cross stay of the series. This reinforcing element, in the form shown, is curved upwardly from the end of the hook and thence outwardly and downwardly about and in offset relation with respect to the edge of the flange, as shown. In this form, both sets of cross stays, at points adjacent the hooks 32, engage the outer faces of the beam 14 when the reinforcement is expanded to aid in limiting the expansion and in holding the reinforcing portions of the caging in proper offset relation.

The form shown in Figs. 10, 11 and 12 is adapted for an angle bar. The alternate cross stays 40 and 41 of the series are arranged in different planes or are offset in transverse direction and each cross stay is bent at right angles intermediate its ends, so that the cross stays fit over the outer faces of the angle bar 42 while the cross stays 41 are spaced therefrom. The cross stays 40 are provided at their ends with attaching elements or hooks 43, which, like those already described are adapted to snugly engage the edges of the bar or beam upon the expansion of the reinforcement to secure the latter thereto, and curved portions 44 connect the hooks to the outer, offset cross-stays 41. When the reinforcement is applied to the beam, the portions of the cross stays 40 and 41 opposite one face of the bar or beam extend back and forth in zig-zag fashion or

- at an angle to one another, as shown in Fig. 11, but, preferably, the portions opposite the other face of the angle bar or beam are maintained in parallel relation, as shown in Fig. 12. This parallel relation between these portions of the cross stays is maintained by providing the outer cross stays 41 with doubled or crimped portions 45 that project inwardly therefrom and overlap the inner cross stays 40. These crimped or doubled portions 45 maintain the portions of the cross stays on one side of the angle bar or beam in parallel relation as the reinforcement is expanded, and also form spacing elements, since they 15 abut against the face of the angle bar and serve to hold the outer reinforcing cross stays 41 in predetermined offset relation.
- The form shown in Figs. 13 and 14 is adapted to be applied to a Z-bar or beam 45. In this form, the alternate cross stays 50 and 51 of the series are arranged in parallel planes which occupy an inclined position, as shown, when the reinforcement is applied to the Z-bar. Each inner cross stay 50 is 25 provided at its ends with horizontally extending attaching elements 52 and 53, which are adapted to snugly engage the upper and lower horizontal faces of the Z-bar when the reinforcement is expanded. Preferably, as 30 shown, the attaching elements 52 are provided at their ends with hook like portions 54 which engage the edge of the lower flange of the Z-bar. Curved connecting portions 55 and 56 extend from the ends of the portions 53 and 54 to the ends of the outer cross stays 51 and these connecting and reinforcing portions are provided with doubled or crimped portions 57 extending inwardly therefrom to form spacing elements. 35 These offset spacing elements overlap the attaching elements 52 and 53 and maintain these portions in parallel relation respectively to the outer reinforcing portions 55 and 56 when the reinforcement or caging is 40 expanded.

It is obvious that numerous changes may be made in the details set forth without the departure from the essentials of the invention as defined in the claims.

50 I claim as my invention:

1. The combination with a structural member, of a supporting caging for the composition covering of said member comprising a length of wire bent back and forth upon itself to form a series of connected cross-stays, the cross-stays of said series being arranged in different planes extending longitudinally of said member and having offset attaching elements hooked over the 55 edges of said member to secure the caging thereto, said cross-stays having portions engaging the outer face of the member to hold other portions thereof in predetermined, offset relation, substantially as described.
- 60 2. A supporting caging for the composition

tion covering of structural members comprising a length of wire bent back and forth upon itself to form an expandable series of connected cross stays, the cross-stays of said series being arranged in different longitudinally extending planes and having laterally projecting attaching elements, said attaching elements and portions of said cross stays being arranged to hook over the flanges and engage the outer face respectively of the member upon the expansion of the caging to hold the other portions of said cross stays in predetermined offset relation relatively to the member, substantially as described. 70

3. A supporting caging for the composition covering of structural members comprising a length of wire bent back and forth upon itself to form an expandable series of connected cross-stays, the cross-stays of said series being arranged in two different longitudinal planes, and attaching and connecting elements extending between the ends of the adjacent cross-stays of said series, said attaching elements and portions of said cross-stays being arranged to hook over and 80 abut against the edges of the structural member to secure the caging thereto, and portions of said cross-stays being arranged to engage the outer face of said structural member to hold the other portions thereof 85 in predetermined offset relation, substantially as described. 90

4. The combination with a structural member, of a supporting caging for the composition covering of said member comprising a length of wire bent back and forth to form a series of connected cross stays, the cross stays of the series being alternately arranged in two different longitudinal planes, said series of cross stays 100 having offset attaching elements securing the caging to the structural member, substantially as described. 105

5. A supporting caging for the composition covering of structural members comprising a length of wire bent back and forth to form an expandable series of connected cross stays, the cross stays of said series being arranged in two different longitudinal planes and said cross stays having laterally 110 offset attaching elements, said attaching elements and portions of said cross stays being arranged to respectively hook over the edges and engage the outer face of the member upon the expansion of the caging to secure the latter thereto with other portions of said cross stays in predetermined offset relation, substantially as described. 115

6. A supporting caging for the composition covering of structural members comprising a length of wire bent back and forth upon itself to form an expandable series of connected cross stays, the cross stays of said series being alternately arranged in different longitudinal planes, and attaching hooks and 120

connecting elements extending between the ends of adjacent cross stays of the series, said attaching hooks being arranged to engage the edges of the member upon the expansion of the caging to secure the latter thereto.

7. A supporting caging for the composition covering of structural members comprising a length of wire bent back and forth upon itself to form an expandible series of connected cross stays, the cross stays of said series being alternately arranged in different longitudinally extending planes, and the intermediate portions between adjacent cross stays of the series being arranged in transverse planes and bent to form offset attaching elements arranged to hook over and abut against the edges of the member and curved, reinforcing elements arranged to extend about the edges of the member in offset relation thereto, substantially as described.

8. A supporting caging for the composition covering of structural members comprising a length of wire bent back and forth upon itself to form a series of connected cross stays, the cross stays of said series being arranged in two different longitudinally extending, substantially parallel planes, the cross stays in one of such planes being ar-

ranged to abut against the outer face of the member and having hooks at their ends arranged to engage the edges of the member, and connecting elements extending between said hooks and the cross stays arranged in the other of said planes, substantially as described.

9. A supporting caging for the composition covering of structural members comprising a length of wire bent back and forth upon itself to form an expandible series of connected cross stays, the cross stays of said series being alternately arranged in two longitudinally extending, substantially parallel planes, the cross stays arranged in one of such planes being arranged to abut against the outer face of the structural member and having hooks at their ends arranged to engage the edges of the flanges of the member upon the expansion of the caging to secure the latter thereto and connecting elements extending between the ends of said hooks and the cross stays in the other of such planes, substantially as described.

DAVID HOMER HAYDEN.
